UNITED STATES PATENT OFFICE.

WILLIAM S. MAYO, OF NEW YORK, N. Y.

IMPROVEMENT IN FENCE-POSTS.

Specification forming part of Letters Patent No. 33,310, dated September 17, 1861.

To all whom it may concern:

Be it known that I, WILLIAM S. MAYO, of the city and county of New York, State of New York, have invented a new and Improved Fence-Post for Ornamental Grounds or for Common Farms, and to be used with wire or with iron or wooden bars, of which the following is a specification:

My improvement consists of a fence-post made of clay and burned in a kiln to the hardness, strength, and durability of common bricks.

One great advantage of this new kind of fence-post is its durability, and consequently its greater cheapness in the end.

For convenience in handling I make each post in several hollow sections of from a foot to two feet in length. When dried, these sections are united and burned together in the kiln into one whole and complete fence-post.

The posts are to be molded with recesses in their sides to receive the fence-rails.

In many parts of the country where timber

and stone are scarce my improvement will be found to be of great utility, as good posts may be made and sold at a cost not exceeding twelve cents, whereas the cost of ordinary wooden fence-posts is from twenty-five to thirty-five cents each.

I am aware that blocks and pots made of burnt clay to receive the lower ends of wooden posts have before been made. These I disclaim. I am also aware that posts made of a cement containing lime, sand, &c., have been cast or built up in molds. These I also disclaim; but,

Having thus described my invention, I claim as new and desire to secure by Letters Patent as an improved article of manufacture—

A fence-post made of clay in an entire piece and afterward hardened by burning, as hereinbefore explained.

WM. S. MAYO.
